THERMALLY COMPENSATABLE TUNABLE CAVITY

Henry Shapiro, New Rochelle, and Robert F. Romero, Mamaroneck, N.Y., assignors, by mesne assignments, to Litton Systems, Inc., Beverly Hills, Calif., a corporation of Maryland

Filed May 31, 1960, Ser. No. 32,992

2 Claims. (Cl. 333—83)

This invention relates to the art of resonant units, more particularly of the temperature compensatable tunable cavity type for high frequency transmission.

As conducive to an understanding of the invention, it is noted that where a resonant unit is of the type such as illustratively shown in Patent No. 2,918,636, dated December 22, 1959, that includes an anode cavity which is tunable by moving a plunger controlled by rods extending from the cavity, since the effective length of the anode cavity substantially determines the operating frequency of the device, where once the plunger has been set by movement of its control rods, changes in ambient and/or operating temperatures cause a change in the effective length of the anode cavity, the operating frequency of the device will be varied.

Where attempts have been made to make the resonant unit temperature stable by constructing the unit with materials with low thermal expansion coefficients, the high cost of such materials renders the units impracticable for ordinary commercial purposes. Furthermore, since materials suitable for resonant units that have a negative thermal coefficient of expansion are not available, it has not been possible intentionally to overcompensate a resonant unit to take care of imperfect temperature compensation elsewhere in elements coupled to the resonant unit.

It is accordingly among the objects of the invention to provide a resonant unit that may readily be fabricated and is strong and sturdy and is not likely to become deranged, and which has an anode cavity that may readily be tuned to a desired operating frequency, and which will automatically adjust the length of the anode cavity with increases in ambient temperature to compensate for thermal variations in the materials used in the construction of the resonant unit or related units.

According to the invention, the resonant unit comprises a cavity in which a plunger is slidably mounted and controlled by rods extending from one end of the cavity, the plunger position substantially determining the resonant frequency of said cavity. The rods which are locked in fixed position when the cavity is tuned are of material that has a suitable thermal coefficient of linear expansion relative to that of the cavity, so that with an increase in ambient temperature, for example, the resonant frequency can be decreased, decreased or held substantially constant.

In the accompanying drawings in which is shown one of various possible embodiments of the several features of the invention,

The single FIGURE is a fragmentary longitudinal sectional view of a resonant unit according to the invention, with parts broken away.

Referring now to the drawings, the temperature compensatable device shown to illustrate the invention is of the type shown in Patent No. 2,918,636, the description and drawings of which are included herein by reference for a more complete showing of the environment in which the present invention is incorporated, and the unit herein shown will only be described to the extent necessary for an understanding of the present invention. Thus

2

such device comprises a metal sleeve 10 which defines the outer wall of the anode cavity 11.

The lower end 41 of sleeve 10 is seated in a circular recess 42 in a bottom plate 43 and is affixed in said recess as by soldering. The plate 43 has a central opening 44 coaxial with sleeve 10 and a pair of diametrically aligned openings 45, the rear edge of plate 43 having a mounting flange 47. Affixed to plate 43 is a disc 51 which has an outstanding axial hub 52 coaxial with the opening 44 in plate 43 and a pair of openings 50 aligned with opening 45.

Extending through hub 52 into sleeve 10 and affixed to the hub as at 53 is a metal sleeve 54 which defines the inner wall of the anode cavity 11 and the outer wall of a grid-cathode cavity 55 more fully described in said Patent No. 2,918,636.

The inner end 58 of sleeve 54 mounts a contact ring 59 which has a plurality of resilient contact fingers 61 designed to make an effective electrical and mechanical connection with the grid ring 62 of tube 34.

Slidably mounted on sleeve 54 in sleeve 10 is a metal plunger 64 by means of which the anode cavity 11 is tuned. The plunger 64 on its inner and outer peripheries has resilient contact fingers 65 which engage the opposed surfaces of sleeves 10 and 54 to provide a good electrical connection and also serve to retain the plunger 64 in set position, the volume of sleeve 11 between plunger 64 and disc 17 defining the active portion of the anode cavity.

To adjust the position of plunger 64 to tune the anode cavity 11, a sleeve 181 is slidably positioned in each of the aligned pairs of openings 45, 50 in bottom plate 43 and disc 51. Each of the sleeves 181 extends through a hub 182 secured to the outer surface of disc 51 and is secured in any desired position by set screws 183.

A rod 66 extends through each of the sleeves 181 and is locked in desired position as by set screws 184 extending through the lower end of the associated sleeve 181.

Thus, referring to the drawing, with the sleeves 181 pushed upwardly as far as possible and locked in position by set screws 183, the effective length of the rods 66 will be from the center line of set screws 184 to the bottom of the plunger 64. With the sleeves 181 moved downwardly, it is apparent that the distance between the set screws 184 and the bottom of the plunger will be increased, thereby materially increasing the effective length of the rods 66 and hence increasing their effectiveness as temperature compensating elements.

According to the invention, the rods 66 connected to plunger 64 are of material such as to have a coefficient of linear thermal expansion with respect to the sleeve 10 as to effect a movement of the plunger 64 with changes in ambient temperature that will increase, decrease or hold substantially constant the resonant frequency of the cavity 10.

Thus, assuming that the cavity is of brass, which has a coefficient of linear thermal expansion of approximately 17.7×10^{-6} per degree centigrade, with a temperature range of from 25 to 300 degrees C., the rods 66 could be of polystyrene, which has a coefficient of linear thermal expansion of approximately 60×10^{-6} per degree C., or phenol-formaldehyde, which has a coefficient of 30 to 40×10^{-6} per degree C.

In both illustrations, the coefficient of linear thermal expansion of the rods 66 is greater than that of the sleeve 10. Hence, based upon the distance of the plunger 64 from the location at which the rods are secured by set screws 184, which depends on the length of the rods and the material of such rods, the position of the plunger in the cavity 11 will vary with changes in ambient tempera-

ture so that the resonant frequency of the cavity may be increased, decreased or held substantially constant.

In practice, the type of material to be used for the rod is determined empirically based on the effective length of the rods 66 by checking the resonant frequency at different temperatures and with different rod materials, and selecting the particular rods which give the desired compensation.

The specific mathematical relations which illustrate the compensation are as follows:

Referring to the drawing, let

K_1 =coefficient of linear thermal expansion of sleeve 10

K_2 =coefficient of linear thermal expansion of sleeve 54

K_3 =coefficient of linear thermal expansion of plunger 64

K_4 =coefficient of linear thermal expansion of plate 43

K_5 =coefficient of linear thermal expansion of block 182

K_6 =coefficient of linear thermal expansion of rods 66

D_1 =inner diameter of sleeve 10

D_2 =outer diameter of sleeve 54

C_0 =effective capacity of plate-grid section of tube 34

L =length of sleeve 10 from point of contact of plate of tube 34 to plate 43

A =thickness of plate 43

B =distance from top face of block 73 to center line of set screws 184

W =thickness of plunger 64

X =distance from point of contact of sleeve 10 to plate of tube 34 to top of plunger 64

C =distance from bottom face of plunger 64 to center line of set screws 184

V =velocity of light

f_0 =resonant frequency of cavity 11

M =mode of resonance ($n=0$, quarter wave; $n=1$, three quarter wave, etc.)

Ignoring the detuning effect of the output 75, the resonant frequency of the plate-grid coaxial cavity 11 is derived as follows:

The characteristic impedance of a coaxial cavity is:

$$(1) \quad Z_0 = 138 \log \frac{D_1}{D_2}$$

At resonance

$$(2) \quad Z_0 \tan \left[\frac{2\pi f_0 X}{V} - n\pi \right] = \frac{1}{2\pi f_0 C_0}$$

$$(2A) \quad 138 \log \frac{D_1}{D_2} \tan \left[\frac{2\pi f_0 X}{V} - n\pi \right] = \frac{1}{2\pi f_0 C_0}$$

Solve for length X

$$(3) \quad X = \frac{V}{2\pi f_0} \left[\tan^{-1} \left(\frac{1}{2\pi f_0 C_0 138 \log \frac{D_1}{D_2}} \right) + n\pi \right]$$

The Equation 3 shows the dependence of the resonant frequency f_0 on the plunger position X ; the two diameters D_1 , D_2 , and the effective tube capacity C_0 . Thus, if the plunger position X can be made to vary as desired, as the ambient and/or operating temperatures change, the resonant frequency can be made to remain stationary or vary in a prescribed manner.

Referring to the drawing, plunger position X is given by:

$$(4) \quad X = L + A + B - C - W$$

For any temperature T , the plunger position X is:

$$(5) \quad X = L[1 + K_1(T - T_0)] + A[1 + K_4(T - T_0)] + B[1 + K_5(T - T_0)] - C[1 + K_6(T - T_0)] - W[1 + K_3(T - T_0)]$$

In the Equation 5 it is understood that L , A , B , C and W are measured at temperature T_0 degrees. The change in plunger position X caused by a change in temperature from T_0 to T degrees is given by:

$$(6) \quad \Delta X = (K_1 L + K_4 A + K_5 B - K_6 C - K_3 W)(T - T_0)$$

Referring to Equation 6, it is clear that by a proper

selection of the material used for rods 66, the plunger to tube plate distance can be made (a) to remain constant; (b) to increase or (c) to decrease, as the temperature increases.

The appropriate value of the coefficient of linear thermal expansion K_6 for each of these conditions where $(K_1 L + K_4 A + K_5 B - K_3 W) = \Sigma$ is

$$(a) \quad K_6 = \frac{\Sigma}{C}$$

$$(b) \quad K_6 < \frac{\Sigma}{C}$$

$$(c) \quad K_6 > \frac{\Sigma}{C}$$

With the relatively simple constructions above described, the effective length of the rods 66 may be appreciably changed independently of the position of the plunger to provide accurate compensation without changing the rod material and it is apparent that with tunable cavities of given physical characteristics, once the physical characteristics of the rods have been determined, production runs of such cavities may be made which will have the desired compensation.

As many changes could be made in the above equipment, and many apparently widely different embodiments of this invention could be made without departing from the scope of the claims, it is intended that all matter contained in the above description or shown in the accompanying drawings shall be interpreted as illustrative and not in a limiting sense.

Having thus described our invention, what we claim as new and desire to secure by Letters Patent of the United States is:

35. 1. A resonant cavity tunable over a broad band of frequencies, comprising a cylindrical sleeve having at least one end wall, a plunger slidably mounted in said sleeve, at least one rod secured at one end to said plunger and extending parallel to the longitudinal axis of said sleeve through said end wall, said rod having a thermal coefficient of linear expansion differing from that of said sleeve to provide a predetermined variation of the position of said plunger in said sleeve with changes in temperature, a member secured to the outer surface of said end wall 40 adjacent said rod, a movable sleeve extending through said end wall and said member, said rod extending through said movable sleeve, means extending through said member to lock said movable sleeve in a predetermined position, and means extending through the outer 45 end of said movable sleeve to lock said rod in a predetermined position, whereby the effective length of said rod will extend from said second locking means to said plunger.

50. 2. A device of the character described tunable over a broad band of frequencies where the maximum frequency is many times the minimum frequency, comprising three coaxial metal sleeves, the outermost sleeve being shorter than the other two sleeves, said outermost sleeve and the second sleeve adjacent thereto defining an anode cavity, 55 said second sleeve and the third sleeve defining a grid-cathode cavity, means to tune said cavities, said tuning means for at least the anode cavity comprising a plunger slidably mounted in said cavity between the outermost sleeve and the second sleeve adjacent thereto, said anode 60 cavity having an end wall, a member secured to the outer surface of said end wall, a movable sleeve extending through said end wall and said member, a rod secured at one end to said plunger and extending parallel to the longitudinal axis of said anode cavity through said movable sleeve, means extending through said member to lock said movable sleeve in a predetermined position, means extending through the outer end of said movable sleeve to lock said rod in a predetermined position, whereby the effective length of said rod will extend from said second locking means to said plunger, said rod having

a thermal coefficient of linear expansion differing from that of said outermost sleeve to provide a predetermined variation of the position of said plunger in said anode cavity with changes in temperature, said second sleeve having an elongated longitudinal slot therethrough in the portion thereof extending beyond the outermost sleeve, a 5 slideable member mounted on the portion of said second sleeve extending beyond the outermost sleeve, an input carried by said slideable member, a contact member electrically connected to said input, carried by said slideable member and insulated therefrom and from said second sleeve, said contact member extending through said slot and resiliently and slidably engaging said third sleeve to feed the input signal into the grid-cathode cavity, the lowest operating frequency of said device being deter- 10

15 mined by the effective maximum length of the anode cavity, the far end of the slot in the second sleeve being at a distance from the inner end of the second sleeve substantially equal to an odd multiple of one quarter wave length which is at least the next larger odd multiple of the number of quarter wave lengths used in the anode circuit.
